UNITED STATES PATENT OFFICE.

PAUL C. SHAFFER, OF NEW YORK, N. Y.

SHADE-ROLLER HOLDER.

1,192,576.

Specification of Letters Patent. Patented July 25, 1916.

Application filed May 2, 1914. Serial No. 836,012.

To all whom it may concern:

Be it known that I, PAUL CLARKE SHAFFER, a citizen of the United States, residing in the borough of Manhattan, city of New York, in the county of New York and State of New York, have invented certain new and useful Improvements in Shade-Roller Holders, of which the following is a specification, reference being had therein to the accompanying drawings, forming part thereof.

My invention relates to means for attaching metal shade roller brackets to metal window casings or parts thereof, such as to the metal trim, commonly to the sheet metal stop strips of the sheet metal casings largely employed in fireproof building construction. These brackets, usually punched from sheet metal, have heretofore commonly been attached to the comparatively thin sheet metal stop strips, or similar sheet metal casing part, by means of screws each holding by only about one and one-half turns of the thread, giving very insecure attachment of the shade roller brackets; and moreover, the tapping and threading of these screw holes occur with the stop strip or other sheet metal casing part in position, and exact spacing and perfect threading of the screw holes are difficult of attainment. Furthermore, the screws are so small that they cannot be handled quickly without dropping them, and much time is thus consumed.

My invention aims to provide for the ready attachment of shade roller brackets with simple and quickly performed operations whereby the brackets are securely fastened and held.

My invention includes a metal bracket having attaching tongues preferably integral therewith projecting through holes in the casing part to the back or inner side of the casing part and there clenched by access had from the outside through free spaces in the holes through which the attaching tongues project.

My invention further includes other features of construction and combinations of parts, as will appear from the following description.

I shall now describe the embodiment of my invention illustrated in the accompanying drawings and shall thereafter point out my invention in claims.

Figure 1 is an inside elevation of the up-

per left corner portion of a sheet metal window frame or casing having a sheet metal stop strip and sheet metal shade roller bracket embodying my invention, the sash being omitted. Fig. 2 is an elevation, partly in section, as viewed from the right in Fig. 1. Fig. 3 is an elevation similar to Fig. 2 of the upper right corner portion of the casing and corresponding parts. Fig. 4 is an elevation of the left hand shade roller bracket of Fig. 1 in position ready for attachment to the stop strip shown in vertical section. Fig. 5 is a vertical section of the bracket and stop strip with the attaching tool in side elevation and the upper one of the attaching tongues of the bracket partly clenched. Fig. 6 is a similar view with the upper tongue of the bracket completely clenched by the other end of the attaching tool. Fig. 7 is an inverted plan of the attaching tool as seen from below in Fig. 5.

The left stop strip 1 (Figs. 1 and 2), right stop strip 2 (Fig. 3), left shade roller bracket 3 (Figs. 1, 2, 4, 5 and 6), and right shade roller bracket 4 (Fig. 3), in all respects not involving my invention, are of usual construction. The sheet metal stop strips 1 and 2 are carried by a usual sheet metal frame or casing 5, these stop strips being of hollow trough shape molding form, as appears in the cross-section of the upper stop strip 6 (Figs. 2 and 3), leaving a considerable open or free space within the stop strips between the stop strips and the inner face of the casing 5. The shade roller brackets are stamped out and punched from sheet metal as heretofore. The left bracket 3 has the usual slotted outwardly projecting central shoulder *a* for the reception of the winding stud of the usual shade roller, and the right bracket 4 has the usual apertured central shoulder *b* for the reception of the pivot stud of the shade roller.

The brackets 3 and 4 have similar flat base portions *c* provided with rearwardly projecting attaching-tongues or attaching-prongs *d* shown as struck down or punched from the central portion of the base *c* so as to leave an opening in the base, the cut made by the punched out tongue *d* not extending to the edge of the base. The flat attaching tongues *d* for each bracket 2 and 3 are shown as turned back toward each other so as to project substantially perpendicularly from

the base *c*, as appears in Fig. 4, and it will be noted that the base or point of origin of each tongue *d* is adjacent to the central outwardly projecting shoulder *a* (of the left bracket 3) or *b* (of the right bracket 4).

5 The stop strips 1 and 2 are provided with round smooth or unthreaded tongue-receiving holes *e* of greater diameter than the width of the attaching tongues *d*, there being two holes corresponding to the two tongues of each bracket and the holes *e* being spaced apart so as to snugly receive the projecting attaching tongues *d* (see Fig. 4 particularly). This larger diameter of the 10 tongue-receiving holes *e* and snug spacing of the attaching-tongues *d* leave free spaces in the holes *e* outwardly from the central shoulder *a* or *b* sufficiently large to permit the tongue *d* to be clenched through the 15 free space by means of a specially formed tongue-clenching tool 7 (Figs. 5, 6 and 7). It will be noted that these free spaces in the holes *e* beside the tongues *d* are of substantially semicircular shape.

20 25 The tongue bending tool 7 is of strong metal, such as steel, and has a middle slightly curved handle portion *f*, an initial tongue-clenching end portion *g* projecting at an obtuse angle to the handle portion, 30 and has, at the other end of the handle portion *f*, a final tongue-clenching end portion *h* bent on a curve to project substantially at right angles to the handle portion *f*. The tongue-clenching portions *g* and *h* are shown 35 as projecting from the same side of the tool and the curve or gradual bend of the handle portion *f* is in a backward direction from the projecting tongue-clenching end portions *g* and *h* so as to prevent accidental 40 twisting of the tool in the hand in use. Also the backward curve of the handle portion *f* provides for the insertion of the tool in the lower tongue-receiving hole *e* by permitting the free end of the tool to clear the upper 45 stop strip 6. It should be noted that the tongue-clenching end portions *g* and *h* are of substantially semicircular shape in cross-section to correspond with the shape of the free spaces left in the holes *e* beside the 50 tongues *d*, these bent end portions *g* and *h* being flattened on their sides adjacent to the handle portion *f*. The attaching tool 7 is provided with fulcrum shoulders *i* between each of the tongue-clenching end portions *g* and *h* and the intermediate handle portion *f*, for limiting the insertion or extent of entrance of these tongue-clenching 55 portions through the tongue-receiving holes *e*, these shoulders being shown as of substantially circular shape flattened on their sides adjacent to the bent end portions *g* and *h*.

60 In the operation of attaching a shade roller bracket to carry out fully my invention the tongue-receiving holes *e*, properly

spaced and of correct diameter, are first drilled in the sheet metal casing part, such as the stop strip 1. Next the shade roller bracket, for example, the left bracket 3 shown in Figs. 1, 2, 4, 5 and 6, is placed in 70 position with the perpendicular attaching tongues *d* projecting through the tongue-receiving holes *e* from the outer accessible side of the stop strip 1 to the inner inaccessible side thereof, as shown in Fig. 4. The 75 slightly bent or obtusely angled tongue-clenching end portion *g* of the attaching tool is now inserted in one of the tongue-receiving holes *e*, for example, in the upper hole, in the semicircular free space beside 80 the attaching tongue *d*. The right-angularly bent end portion *h* of the tool could not be first inserted, as the projecting central shoulder, such as *a*, would obstruct the way, but the slightly bent portion *g* will 85 slip past this central shoulder. The tool 7 is then brought to the position illustrated in Fig. 5, to effect an initial bending over or partial clenching of the attaching-tongue *d*, as clearly appears in this figure. After the 90 initial bending of the attaching tongue *d* illustrated in Fig. 5, the clenching tool 7 is reversed end for end and the right-angularly bent tongue-clenching end portion *h* is inserted in the free space beside the partially 95 clenched tongue, the initial bending of the tongue permitting such end portion *d* to be inserted in the hole *e* past the projecting shoulder *a*. The tool 7 is then brought to the position illustrated in Fig. 6, 100 to effect a final bending over and clenching of the attaching tongue *d*, as is clear from this figure. The fulcrum shoulders *i* in each instance make possible the application of power so as to bend over and effectively 105 clenched the tongue *d*. Without such fulcrum shoulders, the tongue-clenching end portions *g* and *h* would have a tendency to slip too far through the hole *e*, thereby rendering it impossible to properly clenched the attaching-tongue *d*. It should be noted (see Figs. 5 and 6) that the fulcrum shoulders *i* rest upon the projecting end portion of the base *c*, which serves as a fulcrum for the fulcrum shoulders of the attaching tool, obviating 110 any possibility of denting or scarring the comparatively thin sheet metal stop strip 1.

115 After one of the attaching-tongues *d* has been securely clenched, as just described, then the other tongue is similarly clenched, 120 to fix the bracket 3 firmly and securely in place on the stop strip 1, as illustrated in Figs. 1 and 2. The operation of attaching the other bracket 4 (Fig. 3) is the same as that described in reference to the bracket 3. 125 In some instances the lower of the two attaching tongues *d* may be left unclenched or may be dispensed with, since the upper tongue alone will quite firmly hold the bracket in place. With both tongues 130

clenched, however, the bracket is very firmly held, the tongues being preferably clenched oppositely as shown and turned over toward each other, so that the clenched tongues 5 firmly engage and grip the sheet metal stop strips 1 and 2 at the back.

It is obvious that various modifications may be made in the construction illustrated in the drawings and above particularly de- 10 scribed within the principle and scope of my invention.

I claim:

1. A structure embracing coöperating parts, the one being a sheet metal shade roller 15 bracket provided with a projecting attaching tongue, the other being a sheet metal casing part provided with a recess for the tongue permitting passage of the tongue therethrough and access to the tongue from

the outer side to bend the tongue into en- 20 gaging position.

2. A structure embracing coöperating parts, the one being a sheet metal shade roller bracket provided with a plurality of projecting attaching tongues, the other being 25 a sheet metal casing part provided with a corresponding number of recesses for the same permitting passage of the tongues therethrough and access to the tongues from the outer side to bend the tongues into en- 30 gaging position.

In testimony whereof I have affixed my signature in presence of two witnesses.

PAUL C. SHAFFER.
